UNITED STATES PATENT OFFICE.

WILLIAM GEIB, OF MERIDEN, CONNECTICUT, ASSIGNOR TO INTERNATIONAL SILVER COMPANY, OF MERIDEN, CONNECTICUT, A CORPORATION OF NEW JERSEY.

DESIGN FOR A TABLE MAT OR SIMILAR ARTICLE.

Application filed April 4, 1923. Serial No. 5,697. Term of patent 3½ years.

To all whom it may concern:

Be it known that I, WILLIAM GEIB, a citizen of the United States, residing at Meriden, in the county of New Haven and State of Connecticut, have invented a new, original, and ornamental Design for a Table Mat or Similar Article, of which the following is a specification, reference being had to the accompanying drawing, and forming a part thereof.

The figure is a plan view of a mat showing my new design.

The ornamentation shown is repeated entirely around the outer edge and inner circle of the mat.

I claim:

The ornamental design for a table mat or similar article substantially as shown.

WM. GEIB.
